KNOCKDOWN CHAISE LONGUE

Charles P. Molla, New Hyde Park, N. Y., assignor
to Molla Incorporated, New York, N. Y., a cor-
poration of New York

Application March 12, 1946, Serial No. 653,840

3 Claims. (Cl. 155—162)

1

This invention relates to articles of furniture, generally known as chaise-longues, employing a pair of wheels for moving the chaise-longue freely about and over a supporting surface upon lifting the other end portion of the lounge. More particularly, the invention deals with furniture of the kind defined composed of detachably coupled parts or sections whereby when the parts or sections are detached, the complete assemblage can be packed and stored in a relatively small and narrow container, thereby facilitating storage, handling and shipment thereof. Still more particularly, the invention deals with a lounge of the character described employing in conjunction with an adjustable back rest a canopy top forming a hood or closure for the rear head end portion of the chaise-longue, with means for retaining the canopy in extended and collapsed positions in the different positions of the adjustable back rest in the chaise-longue. The novel features of the invention will be best understood from the following description when taken together with the accompanying drawing, in which certain embodiments of the invention are disclosed, and in which the separate parts are designated by suitable reference characters in each of the views; and in which:

Fig. 1 is a perspective view of a chaise-longue in partially set-up position, parts of the construction being broken away and separated, and omitting the covering and facing material usually employed on the canopy and further showing the cushions in dot and dash lines.

Fig. 2 is an enlarged perspective view showing the mounting of the canopy brackets in conjunction with the side rails of the back rest, only part of the canopy being shown and indicating in dot and dash lines the facing material upon the canopy hoops or ribs.

Fig. 3 is an enlarged sectional view through the rear end portion of the chaise-longue, with parts of the construction omitted and parts of the structure broken away.

Fig. 4 is an enlarged sectional detailed view on the line 4—4 of Fig. 3, showing the mounting of the leg and arm rest portions or sections upon the chaise-longue frame.

Fig. 5 is a partial section on the line 5—5 of Fig. 3, on an enlarged scale.

Fig. 6 is a partial section on the line 6—6 of Fig. 1, on an enlarged scale; and

Fig. 7 is a perspective view of a container diagrammatically illustrating in dotted lines the arrangement of the various parts or sections of the knockdown chaise-longue therein.

In the construction of what are generally known as chaise-longues, the same have been constructed of pre-assembled and fixedly secured parts, which form in the resulting article of furniture, a relatively awkward and difficult piece

of furniture to handle. By reason of the awkwardness, the same is susceptible to damage in shipment and transportation, and furthermore, takes up considerable space in storage. Still further, unitary structures of this type and kind have resulted in limited uses by reason of the fact that the average home does not have facilities for winter storage of furniture of this type and kind.

I overcome objections to present type of chaise-longue constructions by constructing the same of detachably coupled and collapsibly related sections whereby the complete article can be packed, stored and shipped in a box or carton, of a length, width and thickness defined by the main body portion or section of the chaise-longue, or of the canopy portion thereof if the same is retained assembled on the chaise-longue or if the latter is employed. In this connection, it will be understood that the inclusion of the canopy top is left optional with the purchaser's choice. At this time, it will also be understood that the chaise-longue may be constructed of what may be considered a single type or of a double type, in which latter instance, the entire piece of furniture is made wider to accommodate two or more people.

Considering Fig. 1 of the drawing, I have shown a single type of chaise-longue, which comprises a base or seat section 10, a back rest section 11, side arm sections 12—12' and a canopy section 13, all of these sections being detachably coupled, including wheel members 14—14' which are detachable with respect to parts of the section 10.

In Fig. 1 of the drawing, the chaise-longue is shown diagrammatically in a partially set-up condition, showing parts separated, parts broken away and removed, in order to simplify the illustration. The section 10 comprises a heavy elongated U-shaped top frame 15, the cross head 16 of which defines the foot end of the lounge. The side members of the frame 15 are curved upwardly, as seen at 17—17' and then downwardly, as seen at 18—18', the ends of the sides of the frame terminating in enlarged bearing portions 19—19'. Inwardly and adjacent the ends 19—19', the frame 15 has downwardly and rearwardly extending wheel supporting portions 20—20', each having inwardly extending axles having large integral collars 22 and reduced ends 23 for supporting a washer 24 held in place by a cotter-pin or similar fastening 25. This construction provides quick and easy coupling and uncoupling of the wheels 14—14' at will.

Welded or otherwise integrally joined with the front corner portions of the frame 15 are downwardly extending legs 26—26'. Between the legs 26—26' and the wheel supporting members 20—20', the sides of the section 10 have a plurality of rods, as at 27—27' for reinforcing the side of the section and also giving character

thereto. In the construction shown, the rods 27-27' substantially conform to the curved contour of the sides of the frame 15. The sides of the frame 15 between the upwardly and downwardly curved portions have inwardly extending brackets 28-28' welded or otherwise secured thereto and one of which is shown in section in Fig. 4 of the drawing. Similar brackets extend outwardly from the wheel supporting members, as shown at 29-29'. These two brackets provide means for coupling the side arm sections 12-12' with the section 10, as later described. The side members of the frame 15 are joined inwardly of and adjacent the members 20-20' by a cross rod 30 and extending between said rod and the cross head 16 and welded or otherwise secured thereto are a plurality of resilient spring bands 31 interfitting with a plurality of cross bands 32 secured to and extending between the sides of the frame 15. The bands 32 aid in supporting the bands 31 in a contour conforming substantially to the contour of the curved sides 17-17' and 18-18' of the frame 15, as will clearly appear from a consideration of Fig. 1 of the drawing:

The bands 31 and 32 form a yieldable or spring like support for the body of the canopy of the chair, thus rendering the same comfortable to sit upon, particularly in the arrangement of cushions on the section 10, as well as on the face of the section 11. In dot and dash lines in Fig. 1 of the drawing, I have indicated at 33 the bottom cushion and at 34 the back rest cushion. The cushions are usually packed in independent wrappers or containers so as to enable a merchant to supply a purchaser with a chaise-longue of a predetermined color or combination of colors with cushions of different colors and/or designs, thereby minimizing stocking of complete cushioned units:

The back or back rest section 11 comprises a small U-shaped frame 35, the cross head 36 of which forms the top of the back rest and 37-37' shows the side arms of the frame 35. The ends of these arms terminate in bearing portions 38-38' adapted to be secured to the bearing portions 19-19' of the frame 19 by bolts, as at 39, thus providing a pivotal mounting of the back rest section 11 upon the section 10, as well as a detachable mounting with respect thereto. The back rest section 11 may be simply swung upon the seat section 10, partly indicated in dotted lines in Fig. 3 of the drawing. Integrally joining the side members 37-37' of the back rest section 11, adjacent the bearings 38-38', is a cross rod 40. Extending between the rod 40 and the cross head 36, are a plurality of spring bands 41, and another spring band 42 extends between the sides 37-37'. As each side or arm section 12-12' is of the same construction, the brief description of one will apply to both. One of these sections is shown rather clearly in Fig. 3 of the drawing, and each section comprises a heavy frame 43 having a leg end 44 joining a horizontal arm rest portion 45 in a curved part 46. At the rear of the arm rest portion 45 is a downwardly and forwardly curved bracket portion 47 having on the inner surface thereof vertically spaced hook-shaped members 48, 49, 50 and 51. The hook shaped members are adapted to receive a back rest supporting rod 52, which is adapted to be supported in any one of the hook members in retaining the back rest section in any one of a number of positions from a more or less upright position, to a reclining position, forming a

relatively flat bed of the complete structure except for the curved contour provided and clearly illustrated in Fig. 1 of the drawing:

The upper end of the leg portion 44 of each section 12-12' has an inwardly extending bracket 53, one of which is shown in section in Fig. 4 of the drawing, adapted to be secured to the bracket 28-28' by bolts 54 passed through apertures in said brackets. The curved end portions 47 terminate at their lower ends in bracket plates 55 adapted to be bolted to the brackets 29-29', as will clearly appear from a consideration of Figs. 1 and 3 of the drawing. In Fig. 1, the brackets 55 and 29 are shown in a partially separated position, ready for assemblage, in order to clearly illustrate this structure. The sections 12-12' each include a pair of rod members 56 welded or otherwise secured to the frames 43, primarily to give greater width to the arm rest portion, and also to strengthen these portions, the rods 56 conform to the general contour of the frames 43.

The above described construction will form a complete chaise-longue suitable for use upon a porch or under trees, awning or other shelters on a terrace or lawn.

However, in some instances, it is desirable to include as a part of the complete structure a canopy top, and in Fig. 1 of the drawing, I have shown the skeleton or framework of the canopy top, omitting the cover or facing material employed to join or couple the various hoops or ribs of the canopy, this being done to simplify the present illustration. The canopy section 13 comprises two similar bracket parts 57, one of which is shown in detail in Fig. 2 of the drawing. These bracket parts have at their outer ends upwardly directed elongated channels 58, in which the ends of a plurality of hoops or ribs 59, 60, 61 and 62 are pivotally mounted. These hoops are of the general curved contour indicated in Fig. 1, and the hoops or ribs are held in extended or open position by a pair of lock levers at each side thereof adjacent the brackets 57, one lever being shown at 63, and being pivoted to the rods 59, as at 64. The other lever 65 is pivoted to the rods 62, as at 66, said levers being pivoted together centrally, as seen at 67. The levers 63 have upwardly and rearwardly extending hand grip portions 68 and inwardly extending lip portions 69 at their pivot ends 67. The lip portions 69 are adapted to overlie the levers 65 in supporting and maintaining the hoops or ribs in extended separated position. However, by lifting the handle members 68, the same may be drawn together into collapsed position, and this operation can take place in any position of the back rest section 11. It will be understood that the canvas or other covering material, as indicated in dot and dash lines at 70 in Fig. 2, of the drawing, will support and maintain the ribs 60-61 in spaced relationship to each other and to the ribs 59 and 62 when the canopy is in open or fully extended position.

The brackets 57 include vertical rod portions 71 having apertured bearings 72 at their lower ends adapted to be mounted on the bolts 39, the rods having at their upper ends inwardly extending U-shaped portions 73 engaging the sides 37-37' to brace and reinforce the bracket mounting upon the back rest section 11.

The hoop or rib 62 includes a pair of supplemental ribs 74 welded or otherwise secured to inner surfaces of upper portions thereof and united, as seen at 75. Welded to the united por-

tions 75 is a downwardly extending coupling plate 76, note Fig. 6, adapted to be bolted to the center strip 41 of the back rest 11, as by bolts 77. From the foregoing, it will be apparent that the complete canopy can be detached by removing the bolts 77 and by removing the bracket ends 57 or the bars 71 thereof from the bolts 39.

It will be understood that the assemblage of the rear hoop or rib 62 with the back rest 11 will maintain said hoop or rib in alinement with the back rest, and the other hoops or ribs are extended forwardly with respect thereto, a distance controlled by the length of the levers and their arrangement upon pivot end portions of the hoops or ribs. In other words, the canopy will be either fully collapsed in a position substantially in alinement with the back rest 11 or fully extended forwardly of the back rest and in either of these positions will move with the back rest in adjusting the same from the fully upright to the fully reclined positions.

A chaise longue constructed of the more or less light framework construction employed can be easily shifted about from place to place by simply lifting on the forward cross head end 16 of the chaise-longue and conveying the chaise-longue on the wheels 14-14' over a supporting surface. On the other hand, the four legs in conjunction with the wheels will firmly support the chaise-longue against shifting on a supporting surface, the legs all preferably have the enlarged feet to prevent piercing or injuring a soft supporting surface. In disassembling the parts, the top or canopy section 13 and back section 11 are removed by removing the bolts 39. In this operation the rod 52 is detached, thereafter the side or arm sections 12-12' are detached, and then the wheels 14-14' are removed. This leaves a relatively thin frame having the depth governed by the height of the front end portion of the section 10 and the distance between the ends 19-19' and the axle ends 21, taking also into consideration the curvature of the section 10 in the upwardly curved sides 17-17'. All of the removed parts can be conveniently packed within the environment of the section 10 for placement in an elongated carton or container 78 in the manner diagrammatically illustrated in Fig. 7 of the drawing.

As previously stated, in some instances, the back section 11 may be retained in its pivotal coupling with the section 10 and simply swung onto the upper surface of the section 10, as indicated in dotted lines in Fig. 3 of the drawing. However, a more compact packaging is possible by detaching the section 11. The parts or sections can be quickly and easily assembled by first mounting the wheels in position, then securing the side sections 12-12' in position, thereafter attaching the back section 11 together with the canopy section 13, if the latter is employed. The rod 52 is then placed in position to support the back rest 11 in this assemblage.

By constructing the bottom or seat section 10 in the concaved contour disclosed, greater comfort is provided to the occupant of the chaise-longue, and further the occupant is retained against downward sliding, as would otherwise be the case. The curvature is slight and not enough to interfere with the comfort of the occupant, either in the upright sitting position, partially reclined position, or in the fully reclined or bed position.

Having fully described my invention, what I claim as new and desire to secure by Letters Patent is:

1. In knockdown chaise-longues comprising a plurality of detachably coupled sections including a back rest section, a base section, and detachable arm rest sections, said base section comprising an elongated substantially U-shaped frame having a front cross head and rearwardly extending sides terminating in pivot ends, means bracing and spacing the rear ends of said sides, the front end of the base section having downwardly extending leg members, the rear portions of the sides of the base section adjacent said pivot ends having downwardly and rearwardly extending wheel supporting members, said members having axle ends, said back rest section being pivoted to the pivot ends of said base section, means for detachably coupling wheels with said axle ends, and means for detachably coupling said arm rest sections to the sides of the base section and said wheel supporting members.
2. In knockdown chaise-longues comprising a plurality of detachably coupled sections including a back rest section, a base section, and detachable arm rest sections, said base section comprising an elongated substantially U-shaped frame having a front cross head and rearwardly extending sides terminating in pivot ends, means bracing and spacing the rear ends of said sides, the front end of the base section having downwardly extending leg members, the rear portions of the sides of the base section adjacent said pivot ends having downwardly and rearwardly extending wheel supporting members, said members having axle ends, said back rest section being pivoted to the pivot ends of said base section, means for detachably coupling wheels with said axle ends, and means for detachably coupling said arm rest sections to the sides of the base section and said wheel supporting members, said arm rest sections including downwardly extending leg portions disposed between the axle ends of the base section and the front legs thereof, and means adjustably supported on the arm rest sections for adjustably supporting said back rest section.
3. In knockdown chaise-longues comprising an elongated base section having suitable supporting means at opposed ends thereof, a back rest section swingably and detachably mounted at the rear of the base section, a canopy detachably connected to said back rest section by means comprising brackets rigidly fixed to the back rest section for supporting a plurality of curved ribs detachably pivoted to said bracket, means detachably connecting one of said ribs on the back rest section, the other ribs being movable about their pivots toward and from said first named rib, and means for extending and collapsing the ribs and for holding the ribs in extended position.
